DESIGN FOR A MOTORCYCLE

Emil H. Erickson, La Crosse, Wis., assignor to Safticycles, Inc., La Crosse, Wis.

Application November 29, 1943, Serial No. 111,807

Term of patent 14 years

(Cl. D90—8)

To all whom it may concern:

Be it known that I, Emil H. Erickson, a citizen of the United States of America, residing at La Crosse, in the county of La Crosse and State of Wisconsin, have invented a new, original, and ornamental Design for a Motorcycle, of which the following is a specification, reference being had to the accompanying drawing, forming a part thereof.

In the drawing:

The rear wall of the package carrier box is provided with ornamentation similar to the side walls.

I claim:

The ornamental design for a motorcycle, as shown and described.

EMIL H. ERICKSON.
